74-416

EX

OF D 12,041

Design No. 12,041, dated November 30, 1880.

UNITED STATES PATENT OFFICE.

RODOLPHE CHRISTESEN, OF NEW BRITAIN, CONN., ASSIGNOR TO THE RUSSELL & ERWIN MANUFACTURING COMPANY, OF SAME PLACE.

DESIGN FOR A STAND FOR FIRE-IRONS, &c.

SPECIFICATION forming part of Design No. 12,041, dated November 30, 1880.

Application filed September 29, 1880. Term of patent 7 years.

To all whom it may concern:

Be it known that I, RODOLPHE CHRISTESEN, of the city of New Britain, county of Hartford, and State of Connecticut, have invented a new and useful Design for Stands for Fire-Irons, &c.; and I do hereby declare that the following specification, taken in connection with the accompanying illustration, forming a part of the same, is a full, clear, and exact description thereof.

The design hereinafter described is adapted to that variety of stands which are employed to hold fire-irons, umbrellas, &c.; and it consists of the following features: The base A of the stand is preferably triangular in shape, and is supported by ornamental feet b. From each angle of the base upright ornamental bars C rise and slightly converge. The upper

ends of these bars are surmounted by leaves c, the stems of which join the base d of a finial, D. The lower portion of the stand is enclosed by ornamental panels E, arranged between the upright bars C.

Although, as shown in the illustration, the base of the stand is of triangular shape, yet it may be of quadraangular or other polygonal form without departing from the general character of the design.

What I claim, and desire to secure by Letters Patent, is—

The design for stands for fire-irons, &c., substantially as described and shown.

RODOLPHE CHRISTESEN.
